UNITED STATES PATENT OFFICE.

JACKSON TIPTON HALE, OF ATLANTA, GEORGIA, ASSIGNOR, BY DIRECT AND MESNE ASSIGNMENTS, TO MILLER SAW-TRIMMER COMPANY, OF PITTSBURGH, PENNSYLVANIA, A CORPORATION OF PENNSYLVANIA.

SHEET-FEEDING MACHINE.

Application filed December 16, 1918, Serial No. 266,912. Renewed April 2, 1925.

To all whom it may concern:

Be it known that I, JACKSON TIPTON HALE, a citizen of the United States, residing at Atlanta, in the county of Fulton and State of Georgia, have invented a new and useful Sheet-Feeding Machine, of which the following is a specification.

My invention pertains to sheet-feeding devices in general, and relates especially to devices for feeding sheets from the position they occupy when separated to an operative position for being printed in a printing press, particularly a flat-bed cylinder press.

An outstanding object of my invention is to enable an increased speed of feeding to be obtained and wear of the parts to be minimized, in a feeding device of the reciprocating type, by reducing the length of the path through which the feed carriage must travel in effecting the transfer of the sheets over the required distance. This is accomplished by providing a single reciprocating feed carriage having sheet-holding means at both its front and rear ends, and causing such carriage to move through substantially one half the distance which the sheets have to traverse. The sheet-holding means at the rear of the carriage transfers the sheet from its separated position to an intermediate position, while the sheet-holding means at the front of the carriage transfers the sheet from such intermediate position to the forward position to which the sheets are to be fed. The carriage thus transfers two sheets at a time, one by the front-sheet-holding means and the other by the rear sheet-holding means. It will be seen that by this construction it is only necessary for the carriage to cover a path substantially one half of the distance through which the sheets have to be moved.

It is another object of my invention to provide a sheet-feeding device which will permit of exceptionally easy access to the press parts, enable the front or rear wing of the feed board to be raised, and allow entry to be had at the rear of the machine, with very little trouble.

It is a further object of my invention to provide a sheet-feeding device which will be an improvement on others heretofore devised in simplicity of construction, ease of

adjustment, and efficiency, certainty and accuracy of operation. Other and further objects of my invention will appear from the following specification taken in connection with the claims annexed thereto.

I have shown in the accompanying drawings, and described in the following specification, a sheet-feeding device embodying my invention. I wish it understood, however, that the invention may be embodied in other forms, and that changes may be made in the embodiment described and shown, without exceeding the scope thereof, as defined in the appended claims.

In the drawings:

Fig. 1 is a plan of a sheet-feeding device constructed in accordance with my invention;

Fig. 2 is a side elevation of the right-hand side of the machine;

Fig. 3 is a side elevation of the left-hand, or operator's, side of the machine;

Fig. 4 is a section taken on the line 4—4 of Fig. 1, the feed carriage, however, being shown in its rearward position;

Figs. 5 and 6 are sections taken respectively on the lines 5—5 and 6—6 of Fig. 1;

Fig. 7 is an enlarged detail view showing parts of the mechanism for raising and lowering the suction feet at the front end of the feed carriage;

Fig. 8 is a view showing certain of the parts of said mechanism in a different position;

Fig. 9 is a plan of part of the mechanism for raising and lowering the suction feet;

Figs. 10 and 11 illustrate the manner of operation of the mechanism for raising and lowering the suction feet;

Fig. 12 is a side elevation of the feeding device, showing the adjustment of the latter to permit raising of the front wing of the feed board;

Fig. 13 is a view similar to Fig. 12, but showing the manner of adjusting the feeding device to permit raising of the rear wing of the feed board, and to allow entry to be had at the rear of the printing press; and

Fig. 14 is a detail side view of one of the mechanical grippers with which the feed carriage is provided.

Like reference characters refer to like parts throughout the following specification and several figures of the accompanying drawings.

5 Referring now to the drawings, in which a complete feeding machine, inclusive of table elevating mechanism, sheet separating mechanism, etc., is broadly indicated, a main frame is provided at the rear of the press, 10 and separated therefrom a sufficient distance to permit entry of an operator between said main frame and the press. The main frame comprises a pair of standards 20, connected in a suitable manner by tie-rods, and secured to the floor by lag screws or the like. In this main frame, between the standards 20, is disposed the stock table 21, the latter being provided with mechanism 15 for automatically elevating it as the stock pile becomes depleted by the feeding away of the sheets.

In the particular machine shown broadly in the drawings, the separation is effected by combing devices. To support the forwardly-extending parts of the combed-forward top sheets of the pile, spaced support fingers 22 are provided. These are secured, so as to be adjustable lengthwise thereon, to a transverse shaft 23, which extends between 25 the standards 20 and is mounted in brackets 24 extending forwardly therefrom. The shaft 23 is provided, at the left-hand side of the machine, with a hand-lever 25. A retaining pin is provided which can pass 30 through the hand-lever and enter the adjacent bracket 24, thereby maintaining the support fingers 22 in a forwardly extended position (Fig. 12). When the pin is withdrawn, the support fingers 22 can drop into 35 a substantially vertical position (Fig. 13).

The upper parts of the main frame standards 20 are disposed substantially parallel with the plane of the feed board of the press and are formed with guideways for receiving 45 the side members 26 of the rear section of the feeder frame. To constitute the said rear section, the said side members are connected together by several tie members, among them a cam shaft 27, fixed shaft 28, 50 and comber drive shaft 29. A central support member 30, through which said shafts pass, is provided substantially half way between the said side members. The rear part 55 of each side member 26 is formed with rack teeth 31 at its upper edge. With these rack teeth (Figs. 1 and 13) engage pinions 32 carried by a shaft 33 which extends across the main frame between the standards 20. By 60 rotating the shaft 33 in one direction or the other, the side members 26, and therefore the whole rear section of the feeder frame, can be moved towards or away from the press, sliding in the guideways of the standards 20.

65 The front section of the feeder frame com-

prises side members 34 supported in suitable guideways in brackets 35, which latter are secured to the press frame. These side members 34 are connected, at their front ends, by the carriage drive shaft 36. The side 70 members 34, and therefore the whole front section of the feeder frame can be moved forward or backward with respect to the press, and can be secured in any desired position of adjustment by means of cap screws 75 37 passing through the brackets 35 and engaging against the side members.

The side members 34 of the front section of the feeder frame form continuations of the side members 26 of the rear section, and 80 during the normal running of the machine, are connected with them. The connection is effected by means of connecting hooks 38 pivoted to the side members 26 of the rear section, which hooks are adapted to engage 85 with pins 39 eccentrically mounted upon small hand levers 40 pivoted to the side members 34 of the front section. A doweled connection is provided between the front side member 34 and the rear side members 90 26, to aid in maintaining perfect alignment between these members.

The cam shaft 27, carried by the rear section of the feeder frame, receives its motion, through a telescoping shaft 41 and suitable 95 gearing (Fig. 2), from one of the shafts of the printing press. A suitable clutch is provided between the cam shaft 27 and telescoping shaft 41, so that the motion of the feeder parts may be arrested at will, regardless of the continued operation of the printing press. The cam shaft 27 is provided with a crank 42, having connected thereto 100 the rear end of a rack 43, the front end of the latter being supported by rollers mounted 105 in a hanger 44 secured to the side member 34 of the front feeder frame section. The rack 43 engages a pinion 45 carried by the outer end of the carriage drive shaft 36. It will be seen that as the cam shaft 27 and 110 crank 42 rotates a reciprocating motion will be imparted to the rack 43 and that this reciprocating motion of the rack will result in a to and fro rocking movement of the carriage drive shaft 36. To permit the 115 front and rear sections of the feeder frame to be separated, the rack 43 may be disconnected from the crank 42 and supported in any desired manner, as, for instance, by the pin and chain arrangement illustrated in 120 Fig. 2.

Cooperating with the shaft 36 is a feed carriage which is provided with mechanical grippers at its rear end and suction feet at 125 its front end. The mechanical grippers at the rear end of the feed carriage seize the sheet in its separated position and carry it forward to an intermediate station substantially half way down the press feed board. The suction feet at the front end of the feed 130

carriage pick up the sheet at its intermediate station and carry it down to the press guides. In the machine illustrated in the drawings, the position of the separated sheet is controlled by feeler fingers 46 cooperating with combers 47. The separated sheet lies with its edge somewhat in advance of the remainder of the forwardly combed portion of the pile, which forwardly combed portion 10 lies upon the support fingers 22 described above.

The feed carriage consists of a pair of racks 48 connected by a front cross bar 49 and a rear cross bar 50. Flanged wheels 51 are carried by the racks, and run upon tracks secured to the feed board 53 of the press. The tracks are divided into front sections 52^a secured to the front wing 53^a of the feed board, middle sections 52^b secured to the 15 middle portion 53^b of the feed board, and rear sections 52^c secured to the rear wing 53^c of the feed board. The track sections are beveled at their adjacent ends, as illustrated in Figs. 12 and 13, so as to permit 20 the wings of the feed board to be swung up as indicated in said figures; and for the same reason the material of the front feed-board wing 53^a is cut away beneath the front ends of the middle track sections 52^b, and the material of the rear feed-board wing 53^c is cut away beneath the rear ends 25 of the said middle track sections.

The reciprocation of the feed carriage is effected by means of pinions 54, which are secured to the carriage drive shaft 36 so as to mesh with the racks 48 (Figs. 1, 3 and 6). The to and fro rocking movement of the carriage drive shaft 36, referred to above, through the pinions 54 and racks 48, effects 40 a to and fro reciprocation of the feed carriage.

Two sets of mechanical grippers 55 are provided at the rear end of the feed carriage. These are identical, one on each side 45 of the machine, and a description of one set will therefore suffice. Referring to the mechanical grippers on the right-hand side of the machine (Figs. 1, 5, 6 and 14), each gripper 55 includes an upper jaw-member 55^a secured to a rock-shaft 56. The latter has its bearing at one end in the right-hand rack 48, and at the other end in a hanger 57 extending downward from the rear cross bar 50 of the feed carriage. Mounted in a recess 55^b of the upper jaw-member 55^a (Fig. 14), and pivoted to the jaw-member at 55^c, is a lower jaw-member 55^d having a jaw 55^e. The shape and disposition of the parts is such that when the lower jaw-member 55^d is rocked so as to move its jaw 55^e forwardly, such jaw will disappear into the recess 55^b of the upper jaw-member 55^a, whereas when the lower jaw-member 55^d is rocked so as to move its jaw 55^e rearwardly, 60 such jaw will emerge from the recess 55^b

and clamp against the lower face of the front of the upper jaw-member 55^a. The lower jaw-member 55^d has pivoted thereto, at a point above its pivot 55^c, the lower end of a link 55^f, the upper end of such link being loosely mounted upon a rod 58 extending lengthwise of the rear cross bar 50, at the rear of the latter. A leaf spring 55^g is secured to the upper jaw-member 55^a, and is provided at its rear end with a roller 75 which engages a suitably shaped cam surface formed on the upper part of the lower jaw-member 55^d in such manner that the spring-pressed roller will maintain the lower jaw-member 55^d in its open or closed position, to 80 whichever of these positions it may have been moved. A set screw secures the upper jaw-member 55^a to the rock-shaft 56, whereby the gripper 55 may be adjusted lengthwise of the rock-shaft, and secured in its 85 adjusted position. When such adjustment is made, all of the parts of the gripper 55 move together, the link 55^f sliding lengthwise on the rod 58. Four of these grippers 55, two on each side of the machine, are 90 shown in the drawings.

To effect the closing of the grippers 55 upon the separated sheet, adjustable rear stops 59 are provided, one at each side of the feed-board, near the rear end of the 95 rear wing 53^c. As the feed frame reaches its rearmost position, the rear stops 59 are engaged by depending arms 60, one of which is carried by each of the rock-shafts 56. By the engagement of the arms 60 with the 100 rear stops 59, the shafts 56 are rocked in a clockwise direction. The effect is that the upper jaw-member 55^a, which had been previously raised, are caused to swing down upon the top of the separated sheet at the 105 front edge of the latter. Owing to the link connections between the lower jaw members 55^d and the rods 58, the jaws 55^e of the lower jaw-members are caused, by this downward movement of the upper jaw-members 55^a, to 110 swing up beneath the separated sheet and clamp it, near the front edge, against the bottom faces of the upper jaw-members 55^a. After the sheet has thus been seized by the grippers 55, the feed carriage makes its forward movement, the grippers carrying with them the separated sheet, and bringing it to an intermediate point approximately half way between the feeler fingers 46 and the press guides. During this forward movement of the carriage, the lower jaw-members 55^d are maintained in their closed condition by the locking action of the rollers carried by the leaf springs 55^g. 115

To open the grippers 55, adjustable front 120 stops 61 (Figs. 1 and 6) are provided, one at each side of the feed board, near the rear end of the front wing 53^a, in position to engage the depending arms 60 on the rock-shafts 56. When the arms 60 strike the ad- 125

justable front stops 61, the shafts 56 are rocked in a contra-clockwise direction, and the upper jaw-members 55^a are thereby raised. By the action of the links 55^c upon 5 the lower jaw-members 55^a, the jaws 55^c of the latter are caused to swing forward into the recesses 55^b of the upper jaw-members 55^a. In this manner the sheet is released from the mechanical grippers 55 at the intermediate point above referred to.

The sheet is thus brought forward to an intermediate position on the feed board 53, from which position, at the next cycle of the machine, it is to be fed forward, by the 15 suction feet at the front of the feed carriage, to the press guides. To retain the sheet in this intermediate position, ready for its further movement at the next reciprocation of the feed carriage, a pair of retaining 20 weights 62 are provided. These weights are adapted to be deposited on the sheet when the latter has reached the intermediate position, and to be raised from the sheet when the latter is again to be moved 25 forward. The weights 62 (Figs. 1 and 4) are mounted upon a weight lever 63 pivoted at 64 to, and extending forwardly from, the 30 central support member 30 of the rear section of the feeder frame. The rear arm 63^a of the weight lever 63 is provided with a cam roller 65 which rides upon a cam 66 mounted on the cam shaft 27. The cam 66 is so shaped as to cause the retaining weights 62 to descend upon the sheet as soon as the 35 latter has reached the intermediate position, and to rise from the sheet just before the latter is to be moved forward from said intermediate position by the suction feet.

Two sets of suction feet 69 are provided 40 at the front of the feed carriage, one set at each side of the machine. Both sets are similarly constructed and mounted, and are actuated alike, and a description of one set will therefore suffice. A pipe 67 is rockably 45 mounted in hangers 68 carried by the front cross bar 49 of the feed carriage. One end of the pipe is adjacent one of the racks 48, and the other end is near the center of the feed board. The outer end of the pipe is 50 closed, and the inner end connected to the pump cylinder, hereinafter to be described. The pipe is formed with a series of holes along its front face, with certain of which holes the suction feet register, depending 55 upon the adjustment of the feet on the pipe. The holes not in use are plugged. A plurality of the suction feet 69 are mounted on the pipe 67, two being shown in the drawings (Figs. 1 and 5). They are provided 60 with air passages, open at the outer lower ends of the feet and registering at the inner ends with the particular holes of the pipe 67 which may be in use. The suction feet are adjustable lengthwise of the pipe 67, 65 and are provided with set screws at their

rear sides. These set screws secure the feet in their adjusted position, and also draw the front parts of the feet into firm engagement with the pipe 67, thus providing an air-tight connection between the pipe and the 70 suction feet. The suction feet are provided, on their tops, with air-regulating valves 70.

At its end adjacent the rack 48, the pipe 67 has secured thereto a cam arm 71 which extends forwardly therefrom and is adapted 75 to be pressed downward, at one stage in the operation of the machine, by a cam 72 (Figs. 1 and 7) mounted on the carriage drive-shaft 36, thereby to cause the suction feet 69 to be moved downward towards the 80 table. The elevating movement of the suction feet from the table is effected by means of a spring 73 secured between one of the hangers 68 and a collar adjustably mounted 85 on the pipe 67.

Loosely mounted on the pipe 67, close to the cam arm 71, is a flat cam lever 74, between which and the cam arm 71 is interposed a latch plate 75 (Figs. 1 and 7-11). The latch plate 75 is formed with elongated 90 slots through which pass the pipe 67 and guide pins 76 extending from the face of the flat cam-lever 74. The body parts of the flat cam-lever 74 and the latch plate 75 are in general similarly shaped, and the 95 outer parts of their front ends are curved upon an arc concentric with the pipe 67. The lower part of the front edge of the latch plate 75 is cut away so as to form a shoulder 77, against which, under certain circumstances, can engage a latch pin 78 extending laterally from the cam arm 71. A coil spring 79 is connected between the flat cam lever 74 and the latch plate 75, and tends to cause the latch plate 75 to slide forwardly 100 with respect to the cam lever 74, the slot and pin arrangement permitting such sliding movement. A front stop pin 80 extending inwardly from the rack 48 limits the 105 downward movement of the forward ends of the flat cam lever 74 and latch plate 75; and a rear stop pin 81, also extending inwardly from the rack 48, limits the upward movement of the said forward ends.

A bevelled cam plate 82 is mounted on the 110 feed board near the front end of the front wing 53^a thereof, in such a position as to be engaged by a cam roll 74^b carried by a tail-piece 74^a mounted on the flat cam lever 74 (Fig. 11). The tail-piece 74^a is made 115 movable about a pivot pin, to permit adjustment of the height of the bottom faces of the suction feet 69 with respect to the feed board at the moment of placing the sheet at the press guides. An adjustable stop 83 is placed on the feed board close beside the cam plate 82 and somewhat beyond the 120 same (Fig. 10) in a position to be engaged by a hook 75^a extending downward and rearward from the latch plate 75.

As the feed carriage makes its rearward movement, the suction feet 69 will be in a raised position, owing to the action of the spring 73. The position of the cam arm 71 with respect to the latch plate 75 will be somewhat like that indicated in Fig. 8, except that the front edge of the latch plate 75 will be being pulled against the latch pin 78 by the spring 79. The suction feet 10 will therefore pass above the sheet which has just been placed against the press guides, without disturbing the latter. When the feed carriage reaches its rearmost position, the suction feet 69 will be above the sheet 15 which, on the previous forward movement of the feed carriage, was fed to the intermediate position by the mechanical grippers 55 at the rear of the feed carriage. At this time the carriage drive shaft 36 will 20 be just concluding its rocking movement in a contra-clockwise direction, and the cam 72 will descend upon the cam arm 71 and depress the latter. During the first part of the descent of the cam arm 71, its latch 25 pin 78 will ride upon the curved front edge of the latch plate 75. When, however, the latch pin 78 has descended far enough, the latch plate 75 will snap forward under the action of the coil spring 79, its shoulder 77 30 passing above the latch pin. The cam arm 71 will move further down, enough to cause the suction feet 69 to engage the top of the sheet beneath them. The downward movement of the flat cam lever 74 and the latch 35 plate 75 will be limited by the front stop pin 80. At this time, suction is applied, so that the sheet will adhere to the suction feet.

As the feed carriage starts its forward movement, the cam 72 will start to rotate 40 in a clockwise direction, and the cam arm 71 will be gradually released from the downward pressure of the cam. Thereby the suction feet are permitted to rise a trifle, under the action of the springs 73 on the pipe 67. When the suction feet have risen 45 this slight distance, further rocking of the pipe 67 is prevented by the engagement of the flat cam lever 74 and latch plate 75 with the rear stop pin 81, and by the engagement 50 of the latch pin 78 against the shoulder 77 of the latch plate 75. Thus, during the forward movement of the feed carriage, the suction feet 69 are maintained in a position in which their front ends are slightly 55 elevated above the feed board, thereby preventing the sheet from rubbing too closely upon the feed board as it is carried towards the press guides.

In order that the sheet may be delivered 60 accurately to the press guides and close to the feed board, the suction feet 69 are depressed again just prior to the end of their forward movement. This is accomplished by the engagement of the cam roll 74^a 65 with the cam plate 82. Such engagement causes a raising of the rear parts of the flat cam lever 74 and latch plate 75 and a consequent depressing of the suction feet. Immediately after this, suction is released from the suction feet, whereby the sheet is deposited on the feed board adjacent the press guides, and the suction feet are raised so as to be in a position to clear the sheet during the rearward movement of the feed carriage. This raising of the suction feet 69 results 70 from the engagement of the hook 75^a of the latch plate 75 with the adjustable stop 83 (Fig. 10). Such engagement stops the latch plate 75 while the cam arm 71 finishes its forward movement with the feed carriage. The effect is that of a rearward movement of the latch plate 75 with respect to the cam arm 71, whereby the shoulder 77 of the latch plate is released from its engagement 75 above the latch pin 78 of the cam arm (Fig. 8). Such release of the cam arm 71 enables the pipe 67 to be rocked upward by the action of the spring 73, thereby elevating the suction feet, ready for the return movement of the feed carriage.

For applying suction to the pipes 67 and the suction feet 69 carried thereby, an elongated pump cylinder 84, disposed longitudinally and centrally of the feed carriage, is provided. It is secured to the cross members 49 and 50, beneath them, and communicates, at its front end, with the pipes 67 by means of connections 85 which may be of any desired kind, provided that they permit of the above-described rocking movement of the pipes. In the pump cylinder 84 slides a suitable piston 86 carried by a piston rod 87, an air relief valve 84^a being provided adjacent the rear end of the pump cylinder, in such a position that it will be 80 uncovered by the piston 86 when the suction feet reach their extreme forward position. The piston rod 87 is connected, by a detachable link 88, to the long arm of a bell-crank lever 89 (Figs. 1 and 4) which is pivoted at 90 to the central support member 30 of the rear section of the feeder frame. The bell-crank lever 89 is provided with a cam roll 91 which rides upon a cam 92 secured to the cam shaft 27. A spring 93 is connected between the bell-crank lever 89 and a bracket on the central support member 30.

When the feed carriage is in its rearmost position, and the suction feet have just 95 descended upon a sheet, the cam roll 91 will leave the high point of the cam 92, the bell-crank lever 89 being pulled rearwardly by the spring 93. This will result in a rearward movement of the piston 86 in the pump cylinder 84, and the application of suction at the suction feet. Maintenance 100 of the suction is effected by the forward movement of the pump cylinder 84 with respect to the piston 86; but as the forward

movement of the feed carriage will at first be relatively slow, owing to the crank motion of the driving device, the application of suction is helped, at first, by inclining the face of the cam 92 so as to permit some further rearward movement of the piston as the feed carriage begins its forward movement. The carriage will be moving at its highest speed when approximately half way through its travel; and, as the suction might be too great at that period, the cam 92 is shaped so as to start to move the piston forward when the carriage is near the center of its travel, thereby diminishing the suction effect. When the sheet has been carried by the suction feet to the required position, the piston 86 passes the air-relief valve 84^a, and suction is thereby released from the pump cylinder 84 and air permitted to enter. In this way the sheet is released by the suction feet at the end of the forward movement of the latter, and deposited on the feed board. Because of the crank movement of the feed-carriage driving device, and the action of the cam 92, the suction is diminished toward the end of the forward movement of the suction feet, and an especially smooth and easy sheet release obtained.

With the machine just starting up, there will be no sheets on the feed board, and therefore no sheet will be present at the intermediate position to be acted upon by the suction feet 69 on the first forward movement of the feed carriage. At such first forward movement, however, the mechanical grippers 55 will transfer a sheet from its separated position on the support fingers 22 to the intermediate position on the feed board, in which intermediate position the sheet will be temporarily secured by the retaining weights 62 descending upon it. Upon the feed carriage returning to its rear-most position after the first reciprocation, the suction feet 69 will seize the sheet thus brought to the intermediate position, the retaining weights 62 rising to release such sheet. At the same time the grippers 55 will seize a second sheet, which will have arrived in the proper position upon the support fingers 22. As the feed carriage moves forward, the first sheet and the second sheet will be carried forward, by the suction feet 69 and the grippers 55 respectively. The first sheet will be carried to the press guides and the second sheet to the intermediate position previously occupied by the first sheet. Thereafter, at each reciprocation, the feed carriage will feed forward two sheets, one sheet being fed by the suction feet 69 from the intermediate position to the press guides, and the other sheet being fed by the grippers 55 from the separated position on the support fingers 22 to the intermediate position.

It will be seen from the above that while a sheet is delivered to the press guides at each reciprocation of the feed carriage yet the feed carriage only moves through a distance substantially one half of the distance between the support fingers 22 and the press guides. This diminution of the distance which the feed carriage must travel permits an increased feeding speed to be maintained, and gives many other beneficial results such as the reduction of wear of the parts, etc. Since it is ordinarily desirable that room shall be left for an operator to enter at the rear of the press, as for instance, when it is desired to insert a form, the stock pile of an automatic feeder is usually placed at a certain distance from the rear end of the press feed board. Thus the distance through which a reciprocating feed device would have to carry the sheet, in order to deliver it to the press guides, will often be greater even than the length of the feed board. It would be difficult to provide an ordinary mechanical movement for reciprocating a feed device to and fro over the entire distance to be covered by the sheets, which would efficiently and safely operate at the high speeds now demanded in machines of this character. This difficulty, however, is completely overcome by the feeding device according to the present invention, wherein the feed carriage has only to travel substantially one-half of the distance through which the sheets are to be fed.

In machines of this character ease of access to the press parts is exceedingly important, and the feeding device of my invention provides for this in a highly advantageous manner. If it is desired to raise the front wing 53^a of the feed board, it is only necessary to turn the machine until the feed carriage is near its extreme rear position, whereupon the front wing can be swung upward about its hinge as though no feed mechanism were present (Fig. 12). If it is desired to raise the rear wing 53^c of the feed board, the small hand levers 40 are actuated to release the hooks 38 which connect the front and rear sections of the feed frame. Then the shaft 33 is rotated, whereupon, through its pinions 32 and the rack teeth 31 on the side members 26 of the rear section of the feeder frame, the said rear section is moved rearwardly, sliding in the guideways of the standards 20 of the main frame. With the feed carriage in its forward position, the rear wing 53^c of the feed board can then be swung upward about its hinge (Fig. 13). By reason of the bevelled arrangement of the ends of the sections of the tracks 52, and the cutting away of the feed board wings, the tracks will not in any way interfere with the swinging of the feed board wings. At the same time, the

sections 52^a, 52^b and 52^c will form a continuous track when the feed board wings are swung downward into their normal position.

Access to the rear of the printing press, to 5 put in a new form, or the like, is had by moving the rear section of the feeder frame rearwardly in the manner described above. The support fingers 22 will usually be dropped as indicated in Fig. 13.

10 Sometimes slippage of the printing press occurs. To adjust for this, the cap screws 37, which clamp the side members 34 of the front section of the feeder frame, may be released and the two sections of the feeder 15 frame moved together, in one direction or the other, by manipulating the shaft 33.

Having thus fully described my invention what I claim as new and desire to secure by Letters Patent is:

20 1. In a paper feeding mechanism, a press feed board divided transversely into front and back wings, a reciprocating carriage mounted on said press feed board, means to actuate said carriage mounted on the 25 frame of the machine above the carriage, and means to separate said carriage actuating mechanism to permit the tilting of one of said wings.

2. A paper feeding mechanism, for use in 30 connection with a printing or other machine, having a sheet advancing carriage adapted to be moved upon a feed board of such machine, and sheet moving members on said carriage and separated in the direction of movement thereof, combined with means for gradually advancing such carriage with an accelerating motion and gradually retarding its motion as it nears its forward limit.

3. In a paper feeding mechanism, a reciprocating carriage, a sheet moving member mounted on the front end of said carriage, and a sheet gripping mechanism mounted upon the back end of the carriage 45 and adapted to carry a sheet at a time from a pile of sheets to a press feed board, said sheet gripping mechanism having gripper elements and two rock shafts supported by hangers at their ends, lever arms extending downward, and stops at opposite ends of the travel of the carriage with which said lever arms engage and adapted to operate the grippers at the limit of the backward stroke, so as to close them onto a 55 sheet and carry the sheet forward on the forward motion of the carriage and drop it onto the press feed board and rise clear of said sheet.

4. In a paper feeding mechanism, a reciprocating carriage, a sheet moving member mounted on the front end of said carriage, a pair of rock shafts mounted in the rear portion of said carriage, gripper elements adjustably secured to the rock shafts, 60 and means to actuate said gripper elements

to engage a sheet when the carriage is at its backward limit.

5. In a paper feeding mechanism, a reciprocating carriage, a pair of alined rock shafts mounted on the rear portion of said carriage, top gripper members fast to the rock shafts, bottom gripper members pivotally mounted on the top gripper members, lever arms fast to the rock shafts, adjustable stops at the rearward and forward 75 limits of travel of the carriage adapted to be engaged by said lever arms to rock the shafts, and connecting links eccentrically connecting the lower gripper members with a stationary portion so that as the shafts 80 are rocked the upper gripper members will descend upon the top of the sheet to be fed and the lower gripper members will rise to engage the bottom of the sheet simultaneously.

6. In a paper feeding mechanism, a reciprocating carriage, a pair of alined rock shafts mounted on the rear portion of said carriage, top gripper members fast to the rock shafts, bottom gripper members pivotally mounted on the top gripper members, lever arms fast to the rock shafts, stops at the rearward and forward limits of travel of the carriage adapted to be engaged by 90 said lever arms to rock the shafts, and connecting links eccentrically connecting the lower gripper members with a stationary portion so that as the shafts are rocked the upper gripper members will descend upon the top of the sheet to be fed and 95 the lower gripper members will rise to engage the bottom of the sheet simultaneously, the said lower gripper members having cam-shaped heads, and springs contacting with said cam-shaped heads to hold the gripper members in different positions.

7. In a paper feeding mechanism, a reciprocating carriage, a pair of alined rock shafts mounted on the rear portion of said carriage, top gripper members fast to the 110 rock-shafts, lower gripper members pivotally mounted on the top gripper members, lever arms fast to the rock shafts, stops at the rearward and forward limits of travel of the carriage adapted to be engaged by 115 said lever arms to rock the shafts, and connecting links eccentrically connecting the lower gripper members with a stationary portion of the carriage so that as the shafts are rocked the top gripper members will descend upon the top of the sheet to be fed and the lower gripper members will rise to engage the bottom of the sheet simultaneously, the said lower gripper members having cam-shaped heads, and springs contacting with 120 said cam-shaped heads to hold the gripper members in different positions, a stationary rod extending across the carriage and supported at intervals thereon and to which the gripper member connecting links are pivoted.

8. In a paper feeding mechanism, a reciprocating carriage, a pair of alined rock shafts mounted on the rear portion of said carriage, top gripper members fast to the rock shafts, bottom gripper members pivotally mounted on the top gripper members, lever arms fast to the rock shafts, stops at the rearward and forward limits of travel of the carriage adapted to be engaged by said lever arms to 70 rock the shafts, and connecting links eccentrically connecting the lower gripper members with a stationary portion of the carriage so that as the shafts are rocked the top gripper members will descend upon the top 75 of the sheet to be fed and the lower gripper members will rise to engage the bottom of the sheet simultaneously, the said lower gripper members having cam-shaped heads and springs contacting with said cam-shaped 80 heads to hold the gripper members in different positions, the stops at the limit of the forward motion of the carriage serving to trip the downwardly extending arms and thereby open and lift the gripper members 85 20 and the springs taking a new position on the cam heads of the lower gripper members and serving to hold the grippers in elevated position out of contact with the sheet.
9. In a paper feeding mechanism, a reciprocating carriage, a cam shaft, and a forwardly projecting weighted arm operatively connected with said shaft, grippers on the rear of the carriage and suction pickers at the front of the carriage, the combination 90 30 being such that the weighted arm is lowered on the sheet as it is released by the grippers and raised as the sheet is taken by the suction pickers.
10. A paper feeding mechanism, having a sheet advancing carriage and means to impart thereto a gradually accelerated advance motion and a gradually retarded motion as the carriage nears the limit of its advance, combined with an air suction pump, hollow 95 40 rock-shafts connected with the pump, pneumatic pickers mounted upon said shafts and having feet adapted to hold a sheet when under vacuum, and a bell-crank lever connected with the pump piston and means to actuate it.
11. In a paper feeding mechanism, a carriage for conveying the paper sheets one at a time from a pile of sheets to the machine to be fed, side frame plates, a cam shaft 100 50 mounted on said plates, a cam on said shaft, an air pump having its cylinder mounted upon the carriage and its piston rod independently supported, a bell-crank lever having one arm cooperative with said cam and the other connected with the air pump piston rod, and a spring applied to the bell-crank lever, and pneumatic pickers supplied by said air pump, the combination and arrangement being such that as the bell-crank lever 105 60 drops off the high point of the cam the 110 spring will be released and act upon said bell-crank lever thereby actuating the air pump and supplying force for lifting the sheet and supporting it until the carriage reaches its advanced position. 70
12. In a paper feeding mechanism, a reciprocating carriage, alined rock-shafts mounted transversely in the leading end of said carriage, pneumatic pickers mounted upon said rock-shafts, and means to supply air to said pickers, combined with means to rock said shafts to lower the pickers on the leading edge of a sheet when the carriage is in its rearmost position, means to again lower the pickers slightly so as properly to deliver the sheet to the machine to be fed, and automatic means to rock the shafts reversely, when the carriage reaches its delivery position to thereby raise the pickers. 75
13. In a paper feeding mechanism, a reciprocating carriage, alined rock-shafts mounted transversely in the leading end of said carriage, pneumatic pickers mounted upon said rock-shafts, and means to supply air to said pickers, combined with a carriage 80 moving shaft, a cam thereon, means interposed between said cam and rock-shafts to cause said rock-shafts to lower the pickers to engage the front edge of a sheet to be fed, when the carriage is in its starting position, 85 a longitudinally movable lever arm on the rock-shaft and interengaging members on said picker lowering means and said lever arm to effect the lifting of the pickers, and a roller lever mounted loosely on the rock-shaft and a stationary cam with which it operates to cause the rock-shafts to rock slightly and lower the pickers to take the sheet under tongues on press guides. 90
14. In a paper feeding machine, in combination with sheet advancing mechanism in stationary side frames, ways to receive the aforementioned slidable side plates, combined with said slidable plates having toothed racks, pinions engaging said racks, 100 95 and a rotary shaft mounted in said stationary side frames and on which the pinions are fixed. 110
15. In a paper feeding machine, in combination with sheet advancing mechanism in side frames ways arranged longitudinally therein, combined with plates slidable in ways, side plates, and means to attach them to and detach them from the sliding plates to facilitate division of the machine. 115 120
16. In a paper feeding machine in connection with sheet advancing mechanism, side frames and vertical supports therefor, between which a sheet advancing carriage is operated combined with frame plates slidable in said frames, side frame plates, brackets to receive and support said side frame plates, ways in said brackets to accommodate sliding of said side frame plates and means of making said side frame plates 125 130

- rigid therein as and when desired, and means to detachably connect the sliding frame plates first mentioned and said side frame plates last mentioned.
- 5 17. In a paper feeding machine in combination with sheet advancing mechanism, frame plates slidable in frames side frame plates, and means to attach them to and detach them from the sliding frame plates to 10 facilitate division of the machine.
18. The combination with a printing press of mechanism for feeding sheets from a predetermined station to said press, said mechanism comprising a sheet-seizing device reciprocable between said station and an intermediate position substantially half way between said station and the press, a second sheet-seizing device reciprocable between 15 said intermediate position and the press, means for reciprocating said devices together, and means for actuating said devices to cause them to seize and release sheets.
19. The combination with a printing press of mechanism for feeding sheets from a predetermined station to said press, said mechanism comprising a carriage, means for reciprocating said carriage between said station and the press, a sheet-seizing device 20 mounted on said carriage, a second sheet-seizing device mounted on said carriage and separated from the first by a distance substantially equal to half that between said station and the press, and means for actuating 25 said sheet-seizing devices to seize and release sheets.
20. The combination with a printing press of mechanism for feeding sheets from a predetermined station to said press, said mechanism comprising a sheet-seizing device reciprocable between said station and an intermediate position substantially half way between said station and the press, a second sheet-seizing device reciprocable between 30 said intermediate position and the press, means for reciprocating said devices together, means for actuating said devices to cause them to seize and release sheets, and means for raising said devices during their 35 movements in a direction towards said station.
21. The combination with a printing press of mechanism for feeding sheets from a predetermined station to said press, said mechanism comprising a carriage, means for reciprocating said carriage between said station and the press, a sheet-seizing device mounted on said carriage, a second sheet-seizing device mounted on said carriage and 40 separated from the first by a distance substantially equal to half that between said station and the press, means for actuating said sheet-seizing devices to seize and release sheets and means for raising one of 45 said sheet-seizing devices during the move- 50 ment of said carriage from said press towards said station.
22. The combination with a printing press of mechanism for feeding sheets from a predetermined station to said press, said mechanism comprising a sheet-seizing device reciprocable between said station and an intermediate position substantially half way between said station and the press, a second sheet-seizing device reciprocable between 55 said intermediate position and the press, means for reciprocating said devices together, means for actuating said devices to cause them to seize and release sheets and means for retaining sheets in said intermediate position between their release by said first-named device and their seizing by 60 said second named device.
23. The combination with a printing press of mechanism for feeding sheets from a predetermined station to said press, said mechanism comprising a carriage, means for reciprocating said carriage between said station and the press, a sheet-seizing device 65 mounted on said carriage, a second sheet-seizing device mounted on said carriage and separated from the first by a distance substantially equal to half that between said station and the press, means for actuating said sheet-seizing devices to seize and release sheets and means for retaining sheets in position between their release by one of 70 said devices and their seizing by the other.
24. The combination with a printing press having a feed board associated therewith, of means for feeding sheets to said press comprising a carriage, a sheet-seizing device mounted on said carriage toward the front thereof, a second sheet-seizing device mounted on said carriage toward the rear 75 thereof, said devices being separated by a distance substantially one half of that to be traversed by the sheet in being fed to the press, means for reciprocating said carriage over said feed board, and means for actuating said devices to seize and release sheets.
25. The combination with a printing press having a feed board associated therewith, of means for feeding sheets to said press comprising a carriage, a sheet-seizing device 80 mounted on said carriage toward the front thereof, a second sheet-seizing device mounted on said carriage toward the rear thereof, said devices being separated by a distance substantially one half of that to be 85 traversed by the sheet in being fed to the press, means for reciprocating said carriage over said feed board, means for actuating said devices to seize and release sheets, and means for retaining sheets in position on 90 said feed board between being released by one of said devices and being seized by the other.
26. The combination with a printing press having a feed board associated therewith, 95

- of means for feeding sheets to said press comprising guiding means associated with said feed board, a carriage cooperating with said guiding means to reciprocate over said feed board, a sheet seizing device associated with said carriage toward the front thereof, a second sheet-seizing device associated with said carriage toward the rear thereof, said devices being separated by a distance substantially one half of that to be traversed by the sheet in being fed to the press, means for reciprocating said carriage on said tracks, and means for actuating said devices to seize and release sheets.
- 10 27. The combination with a printing press having a feed board associated therewith, of means for feeding sheets to said press comprising guiding means associated with said feed board, a carriage cooperating with said guiding means to reciprocate over said feed board, a sheet seizing device associated with said carriage toward the front thereof, a second sheet-seizing device associated with said carriage toward the rear thereof, said devices being separated by a distance substantially one half of that to be traversed by the sheet in being fed to the press, means for reciprocating said carriage on said tracks, means for actuating said devices to seize and release sheets, and means for retaining sheets in position on said feed board between being released by one of said devices and being seized by the other.
- 15 28. The combination with a printing press having a feed board associated therewith, of means for feeding sheets to said press comprising tracks associated with said feed board, a carriage rolling on said tracks, a sheet-seizing device mounted on said carriage toward the front thereof, a second sheet-seizing device mounted on said carriage toward the rear thereof, said devices being separated by a distance substantially one half of that to be traversed by the sheet in being fed to the press, means for reciprocating said carriage on said tracks, and means for actuating said devices to seize and release sheets, and means for retaining sheets in position on said feed board between being released by one of said devices and being seized by the other.
- 20 29. The combination with a printing press having a feed board associated therewith, of means for feeding sheets to said press comprising tracks associated with said feed board, a carriage rolling on said tracks, a sheet-seizing device mounted on said carriage toward the front thereof, a second sheet-seizing device mounted on said carriage toward the rear thereof, said devices being separated by a distance substantially one half of that to be traversed by the sheet in being fed to the press, means for reciprocating said carriage on said tracks, means for actuating said devices to seize and release sheets, and means for retaining sheets in position on said feed board between being released by one of said devices and being seized by the other.
